SEGMENTAL PULP WHEEL

George B. Rickard, Niagara Falls, N. Y., assignor
to The Carborundum Company, Niagara Falls,
N. Y., a corporation of Delaware

Application June 18, 1937, Serial No. 148,972

6 Claims. (Cl. 51—207)

This invention relates to the manufacture of pulp wheels and particularly to means for clamping segments of a pulp wheel more firmly when the wheel is subjected to heavier loads with consequent rise of temperature.

Many of the difficulties in maintaining segmental pulp wheels in good condition arise from large changes of temperature which tend to loosen the segments from their mountings. In northern latitudes the temperature of the outer parts of a pulp wheel in winter may range from -40° Fahrenheit when not in use to nearly the boiling-point of water when the pulp wheel is being operated under heavy load. Clay-bonded abrasive segments containing silicon carbide or fused alumina abrasive grain, which have been bonded by heating the molded article to the temperature of vitrification, have coefficients of thermal expansion which are considerably less than those of the iron or steel drums on which they are usually mounted. The coefficients of expansion of such vitrified segments may be only half that of their metal supports. It is therefore desirable, if possible, to mount the abrasive segments in such a manner that increase of load on the pulp wheel will not result in loosening of the clamps, but will tend to tighten the clamping means. One of the principal effects of increase of load is greatly increased friction between the periphery of the wheel and the logs which are pressed against it. The heat developed by this friction is conducted rapidly from the hot liquids which spread over the surface of the wheel to adjacent interior parts of the wheel and to metal connections.

One of the objects of the invention is to provide clamping means by which one or more abrasive segments can be clamped to a support by means accessible from the ends of the pulp wheel. Another object of the invention is to make the clamping means just referred to of such a character that there will be automatic compensation tending to resist loosening of the segments from the clamps and from the supporting base when the temperature of the pulp wheel rises.

The improved mounting and clamping means for holding the abrasive segments against their support are illustrated by the accompanying drawings in which:

Figure 1 is a side view (perpendicular to the axis of rotation) of a segmental pulp wheel that has been partly broken away to show the method of mounting the segments on their support and means for applying the necessary pull to firmly anchor the segments to the support;

Figure 2 is a partial end view of the segmental pulp wheel shown in Figure 1 with a portion of the terminal covering broken away to give an end view of a toggle clamp;

Figure 3 is a partial end view of a cast metal hub having inwardly extending pockets or housings in which the clamp control mechanism is to be inserted;

Figure 4 is a section on the line IV—IV of Figure 3;

Figure 5 is a side view of one of the screws used in regulating the pressure of a clamp against an abrasive segment;

Figure 6 is a side view of a pivot for a pair of toggle links, which pivot is threaded also for engagement with the regulating screw; and

Figure 7 is a side elevation of the segmental wheel mounted on a driving shaft.

Referring to the drawings in detail, abrasive segments 2 are shown in Figure 2 as mounted on a slotted metal hub 3 which has a periphery of general polygonal shape. The slots 4 each communicate with the interior of a pocket 5 which is used as a housing for part of the clamping mechanism and for the means which regulates the intensity of clamping. The inwardly projecting metal pockets 5 are embedded in the cement core 6. The inwardly projecting pockets 5 and the peripheral portions 7 on which the abrasive segments rest are parts of one continuous casting which forms the hub 3. Each abrasive segment is formed with a T-shaped slot 8 into which a T-shaped clamping member 9 is inserted.

In the embodiment of the applicant's pulp wheel illustrated in Figure 1, the broken section shows two toggle clamping systems, each of which systems may be used to clamp one or more abrasive segments. Each toggle clamping system comprises a T-shaped clamping member 9 which fits into the T-shaped slot 8 in the base of its abrasive segment, a pair of clamping bars 11 that are contained in the pocket 5 which communicates with the slot in the abrasive segment, outer links 12 which connect the T-shaped clamping member 9 with the toggle pivot 13, inner links 14 that connect the clamping bars 11 with the toggle pivot 13, and a regulating screw 15 which is oppositely threaded at its opposite ends and which engages threaded holes in two oppositely disposed toggle pivots 13.

Each regulating screw 15 has a square end 16 which may be engaged by a wrench to push the pivot members 13 further apart or pull them closer together and hence tighten or loosen the

clamping of the abrasive segment with respect to its metal support.

In order to minimize the effects of expansion of the links 12 and 14, they are made of a nickel-5 steel alloy having a very low coefficient of expansion. The clamping members 9 and 11 can be made of structural steel having a coefficient of expansion that does not differ much from that of iron. The regulating screw 15 can be made, 10 for example, of a bronze alloy which has a coefficient of expansion much greater than that of iron, such as phosphor bronze.

The purpose of this construction is to provide 15 automatic temperature regulation of the clamping action. Increase of temperature of the assembly tends to push the oppositely disposed pivots 13 further apart and hence draw the abrasive segment toward its support, thus decreasing the tendency of the segment to become 20 looser as the temperature of the pulp wheel rises. When the operation of the pulp wheel ceases and the temperature of the wheel assembly falls, the rapid contraction of the regulating screw 15 tends to lighten the pressure of the clamps on 25 the abrasive segment and hence lessens the danger of the building up of destructive pressures if the metal support should contract more rapidly than the abrasive segments.

In the preparation of the wheel mounting, the 30 casting 3 is provided with a concrete core 6 of the form indicated in the upper half of Figure 1. The cylindrical metal sleeve 17 and the internally tapered metal sleeves 18 are centrally and symmetrically located inside the casting 3. A metal spiral or helix 22 is placed outside the sleeves 17 and 18. End plugs not shown are provided to form the frustoconical surfaces 19 and 20 when the concrete mixture is poured inside the casting 3. After the concrete has hardened, 35 terminal bushings (not shown) are fitted inside the tapered sleeves 18. Each of these bushings has an external tapered surface which is complementary to the internal tapered surface of the sleeve 18 into which it fits, and each bushing has an internal cylindrical surface into which an assembly 40 shaft (not shown) fits snugly. The wheel center (comprising principally the casting 3, the reinforced concrete core 6, the sleeves 17 and 18, and the terminal bushings) is then mounted on the assembly shaft which in turn is mounted horizontally in bearings which permit turning the center by hand. The center is thus turned until 45 one of the faces of the polygonal exterior surface of the casting 3 is brought into a horizontal upper position for mounting the first row of abrasive segments in position. These segments (indicated at the top of Figure 1) may be mounted one at a time or in groups of several segments which have been cemented together to 50 form a row of segments across the wheel face.

A thin layer of lead or other suitable yielding material is placed on the upper horizontal surface of the casting 3 as a packing material. A row of segments 2, as described in the paragraph next 55 above, is then placed in position on the packing layer, six segments being indicated in the row at the top of Figure 1. A suitable cold setting cement or heat hardenable cement is used to join adjacent segments to each other. Where several segments are to be joined together by means of a heat hardenable cement, the surfaces to be joined are painted with the heat hardenable mix and the segments brought together before assembly on the hub. A group of segments with 60 joints of heat hardenable cement is heated to set 65

the cement and is cooled before the group is placed on the hub member 3. The toggle clamps are then inserted into the pockets 5 and T-shaped slots 8. A thin packing of sheet lead is provided between the T-shaped clamping member 9 and the adjacent shoulders of the abrasive segment. In Figure 1 two toggle clamps are shown as holding three segments each on the supporting hub 3. The clamping pressure is adjusted from either 10 end of the assembly by applying a wrench to the square ends 16 of the respective toggle control screws 15.

The hub is then turned until one of the adjacent exterior flat surfaces of the hub 3 is in a horizontal position. A resilient water-proof 15 packing is provided between the two adjacent transverse rows of segments. Such a packing may be made, for example, from two sheets of fabric, which have been impregnated with a heat hardenable synthetic resin, a layer of vulcanizable rubber being inserted between the two impregnated sheets of fabric. The sheets and the intermediate layer are then heated to a temperature which will harden the synthetic resin and vulcanize the rubber. The cured composite sheet 20 forms a strong resilient packing between adjacent rows of segments, that is for the joints which are disposed in radial planes.

Other rows of abrasive segments are then 25 built up in succession in a similar manner until the segmental abrasive rim is completed on the peripheral surface of the hub. The wheel is subsequently provided for operation with driving flanges as shown at 31 in Figure 7.

In Figure 1 each toggle control screw 15 is indicated as in use for regulating the clamping 30 pressure on three segments. A toggle control can, however, be provided for one or more segments in a row as thought desirable.

After the segments have been mounted firmly 35 on their metal supports by adjustment of the toggle controls, the ends of each pocket 5 are closed by means of cover plates 25 as indicated in Figure 2, these plates being fastened by means of screws 26. The ends of the hub can be further 40 sealed by means of cold-setting cement, fibrous 45 packing or other suitable material.

If any particular segment of the completed 50 wheel should be found to be defective, the nearest cover plate 25 can be removed and the toggle 55 clamp loosened by turning the screw 15 in the proper direction with a wrench. The segment to be removed is then held only by the joint material between it and the adjacent segments. As 60 this joint material is structurally much weaker than the abrasive material of the defective segment, the necessary number of segments in the row that contains the defective segment can be 65 removed with suitable tools.

The improved mounting for abrasive segments 65 has a number of advantages from the point of view of ease of assembly and from the point of view of the provision for quickly releasing the clamping pressure on one or more segments when it is necessary to replace them. One of the 70 principal features is the automatic temperature control of clamping pressure on the segments.

The abrasive segments can be made by bonding, for example, silicon carbide or fused alumina grain with a clay bond, the molded segments 75 being heated to the temperature of vitrification of the bond.

While many variations can be made in the materials of which the abrasive segments are made as well as in the materials used for joining the 75

segments and for making the toggle clamping system, the invention is defined within the compass of the following claims.

I claim:

- 5 1. In a segmental abrasive wheel means for clamping the abrasive segments to a rotatable support, said means comprising for each segment a clamping member in contact with one or more shoulders of said abrasive segment, a second 5
10 clamping member in contact with one or more shoulders in a recess in the adjacent portion of the rotatable support, manually operable means for drawing said two clamping members toward each other to clamp the abrasive segment firmly 15 to the rotatable support, and automatic means for pressing said clamping plates toward each other when the temperature of the wheel rises.
2. In a segmental abrasive wheel means for clamping the segments to a metal support, said 20 means comprising a pair of spaced toggle clamps adapted to vary the pressure between a clamping plate and the base of an abrasive segment, and a screw which passes through the pivots of both 25
23 toggle clamps in oppositely threaded engagement so that rotation of the screw in one direction tightens the clamps and rotation in the opposite direction loosens the clamps.
3. In a segmental abrasive wheel means for clamping abrasive segments to a metal hub, said 30 means comprising a clamping member in contact with one or more shoulders on the base of an abrasive segment, a second clamping member in contact with one or more shoulders in a recess 35 in the adjacent portion of the hub, one or more
35
40 toggle arms pivotally connected to one end of the segmental clamping member and to a pivot member disposed between the abrasive segment and the hub, one or more toggle arms pivotally connected to the corresponding end of the hub clamping member and to said pivot member, a

corresponding toggle group connecting the opposite ends of the segmental clamping member and the hub clamping member to a similar intermediate pivot member, and a screw which passes through both pivot members in oppositely threaded engagement so that rotation of the screw in one direction tightens the clamps and rotation in the opposite direction loosens the clamps.

4. The clamping means described in claim 3 10 in which the toggle arms are made of a metal having a low coefficient of expansion and in which the screw that connects the pivot members is made of a metal having a high coefficient of expansion so that rise of temperature of the 15 wheel tends to bring the segmental clamping member closer to the hub clamping member.

5. The clamping means described in claim 3 20 in which the toggle arms are made of nickel steel of the Invar type and in which the screw that 25 connects the pivot members is made of phosphor bronze so that rise of temperature of the wheel tends to bring the segmental clamping plate closer to the hub clamping plate, thereby increasing the clamping pressure at operating temperature.

6. The abrasive wheel described in claim 1 in which the hub is in the form of a metal casting having a slotted peripheral surface for supporting correspondingly slotted abrasive segments, 30 clamping means extending from a recess in each abrasive segment through corresponding slots in the segment and hub to a toggle control housing extending inwardly from the peripheral surface of the casting and opening out from the slot 35 therein, and a cement core in intimate contact with the inner surface of the hub and holding the housing embedded therein.

GEORGE B. RICKARD. 40
